[57] CLAIM

The ornamental design for a tiered insert for a display tray, as shown and described.

DESCRIPTION

FIG. 1 is a perspective view of a tiered insert for a display tray showing my new design;

FIG. 2 is a front elevational view thereof;

FIG. 3 is a rear elevational view thereof;

FIG. 4 is a right side elevational view, the broken line illustrating a display tray is shown for environmental structure only and forms no part of the claimed design;

FIG. 5 is a left side elevational view thereof;

FIG. 6 is a top plan view thereof;

FIG. 7 is a bottom plan view thereof;

FIG. 8 is a perspective view of a second embodiment of the tiered insert for a display tray shown in FIG. 1;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a perspective view of a third embodiment of the tiered insert for a display tray shown in FIG. 1;

FIG. 16 is a front elevational view thereof;

FIG. 17 is a rear elevational view thereof;

FIG. 18 is a top plan view thereof; the side elevational views being identical to FIGS. 4 and 5 respectively;

FIG. 19 is a perspective view of a fourth embodiment of the tiered insert for a display tray shown in FIG. 1;

FIG. 20 is a front elevational view thereof;

FIG. 21 is a rear elevational view thereof; and

FIG. 22 is a top plan view thereof, the side elevational views being identical to FIGS. 11 and 12 respectively.
